CONTROL DEVICE FOR RINGLESS YARN CARRIER ATTACHMENTS

Herbert Erich Haehnel, West Reading, Pa., assignor to Textile Machine Works, Wyomissing, Pa., a corporation of Pennsylvania

Application February 27, 1943, Serial No. 477,462

8 Claims. (Cl. 66—127)

This invention relates to straight or full-fashioned knitting machines and more particularly to means arranged to prevent accidental change in the predetermined operation of certain selective yarn feeding mechanisms of such machines.

It is common practice to knit the greater portion of the blanks for full-fashioned hosiery according to the "ringless" principle, that is, with a plurality of yarns, usually three. For this purpose, it is standard practice to provide a friction box arrangement having automatic yarn carrier rod selector means for connecting and releasing the multiple yarn carrier rods carrying out the "ringless" knitting. However, when knitting certain areas of such a ringless stocking blank, only a single yarn is used and for this purpose a standard friction box of the full-fashioned knitting machine is commonly employed to reciprocate a single yarn carrier rod. During operation of the single thread carrier, the friction box with automatic carrier selecting means is released from operation, is disconnected from the friction-box rod of the machine and moved to inactive position.

When the automatic carrier selecting mechanism for "ringless" knitting is again put into operation, after a single rod has been operated as explained, the carrier rod connecting means associated with the friction box must be precisely positioned for engagement with the first operating yarn carrier rod to be driven to lay yarn for the initial course of the "ringless" portion. Certain automatic carrier rod selecting mechanisms heretofore available have proven unreliable and unsatisfactory in this respect in that the first or starting yarn carrier rod has not always been engaged as intended, with the result that the fabric was unintentionally pressed off under these conditions. Further, sometimes the wrong carrier rod has been engaged or mechanical interference has occurred between a dog or similarly acting member or portion on the carrier rod and an engaging member or portion of the selecting mechanism.

One object of my invention is to provide novel means in straight or full-fashioned knitting machines for overcoming the mentioned and other difficulties.

Another object is to provide such means which will invariably function to operate only the proper yarn carrier rod at the start of the "ringless" yarn laying cycle.

It is also an object of my invention to provide such means which will prevent moving of the selector means into carrier rod engaging posi-

tion with the first carrier rod to be operated when the selector means is improperly set for operation.

With these and other objects in view which will become apparent from the following detailed description of the illustrative embodiment of the invention shown in the accompanying drawings, my invention resides in the yarn carrier rod operating mechanism comprising the novel elements, features of construction and arrangement of parts in cooperative relationship, as hereininafter more particularly pointed out in the claims.

In the drawings:

15 Figure 1 is a cross sectional view through a full-fashioned knitting machine and shows my invention applied thereto;

Fig. 2 is a view as seen by looking in the direction of the arrows 2—2 on Fig. 1, however on an enlarged scale relative to the latter.

Fig. 3 is a cross sectional view taken along the line 3—3 of Fig. 2;

Fig. 4 is a back elevation of a portion of the mechanism shown in Fig. 1 as viewed in the direction of the arrows 4—4 and enlarged relative to Fig. 1;

Fig. 5 is a view similar to Fig. 4 but with the parts in different relative positions;

Fig. 6 is an enlarged view of the mechanism shown at the upper part of Fig. 1;

Fig. 7 is a sectional view taken substantially along the lines 7—7 of Fig. 2 with parts omitted in order to more clearly show the control means of the invention; and

Fig. 8 is a cross sectional view taken substantially along the line 8—8 of Fig. 5.

In the drawings and description, only the means necessary to a complete understanding of the invention have been specifically set forth; further information as to the construction and operation of other related, usual and well known knitting machine elements, mechanisms, etc., may be found in one or more of the following publications:

1. Pamphlet entitled—Full-Fashioned Knitting Machines—published and copyrighted by the Textile Machine Works, Reading, Pennsylvania, in 1920.
2. Three catalogs entitled—The "Reading" Full-Fashioned Knitting Machine Parts Catalog—published and copyrighted by the Textile Machine Works, in 1929, 1935 and 1940, respectively.

3. Booklet entitled—The “Reading” High-Production Full-Fashioned Knitting Machine—which forms a supplement to the above noted 1940 Parts Catalog of the Textile Machine Works, and which booklet is a publication of the Textile Machine Works, and was copyrighted by the latter in 1940.
4. Pamphlet entitled—Knitting Machine Lectures—published by the Wyomissing Polytechnic Institute, Wyomissing, Pennsylvania, in 1935.

The machine disclosed herein to which my invention is applied is a well-known type of full-fashioned knitting machine and has, on the friction-box for “ringless” knitting, a carrier rod selecting means of the plural element or two-arm form.

Referring to Fig. 1 of the drawings, I have shown therein a conventional full-fashioned knitting machine in which the usual frame members comprise a center frame 11 supporting a front beam 12, a back beam 13, a front bed 14 and a center bed 16. The center bed 16 carries a series of brackets, one of which is shown at 17, for supporting the carrier rods 1 to 8, inclusive, for sliding movement during feeding of the yarn to the loop forming elements of the machine, i. e., the needles, sinkers and dividers, not shown. Full speed and half speed friction rods 18 and 19, respectively, operate the carrier rods by means of the usual friction box devices of the machine.

Certain of the carrier rods, i. e. carrier rods 1, 2, and 3 are operated to feed yarn to the loop forming elements alternately in predetermined sequence to produce “ringless” fabric. For this purpose, there is provided a carrier rod alternating attachment 25 of the two lever type (Figs. 1, 2, 6 and 8), shown generally on pages 197 to 203 of the aforesaid 1940 Parts Catalog, and comprising a frame member or friction box 26 having frictional engagement with the full speed friction rod 18 through the usual friction shoes, (not shown). The friction box 26 is also provided with a portion 28 having sliding engagement with the half speed rod 19 (Figs. 6 and 8).

The frame member of friction box 26 is provided with upright members or arms 30 (Figs. 2 and 6) between which are disposed elements or levers 32 and 33 rotatably mounted on a shaft 34 (Fig. 8) eccentrically carried on a shaft 37 secured in the arms 30. The shaft 34 may be turned about the shaft 37 by means of a lever 38 which is secured to the eccentric shaft 34 and carries a detent member 41 which extends into an opening 45 of the shaft 34 and is adapted to engage a flat portion 42 on the shaft 37 (Fig. 8) in either one of two positions of the lever 38 for reasons hereinafter set forth. Said two positions of lever 38 are substantially 180° apart and, consequently, the detent 41 and the opening 45 for the detent in shaft 34 are made round so that detent 41 can be turned to permit its flattened inner end to engage flat portion 42 in either position of lever 38. The levers 32 and 33 have extensions 35 and 36, respectively, spaced by bolts 43, having jam nuts 44, from extensions 47 and 48 of cam levers 51 and 52, respectively, which are also pivotally mounted on shaft 34 and along side of levers 32 and 33, respectively. The cam levers 51 and 52 have cam followers 53 and 54, respectively, for engagement with cams 57 and 58, respectively, disposed between arms 30, on an auxiliary cam shaft 59 and rotated therewith by pawl and ratchet means (not shown)

operated from the usual connecting bar of the machine in a manner similar to that shown and described in the F. Autem Patent No. 2,219,733, issued October 29, 1940, and shown in the aforesaid 1940 Parts Catalog. Tension springs 62 connected between extensions 63 and 64 also on levers 32, 51 and 33, 53, respectively, transmit a pull between them to maintain the extensions 35 and 36 normally as close to extensions 47 and 48 as permitted by bolts 43 and springs 67 connected between the levers 32 and 33 and the friction box 26 (Fig. 8) urge the levers 32 and 33 in the clockwise direction, as viewed in Fig. 8, to maintain the followers 53 and 54 in contact with the cams 57 and 58, respectively, by the clockwise torque thereby transmitted to levers 51 and 52. The bolts 43 in extensions 35 and 36 contact with extensions 47 and 48 to hold levers 32 and 33 in the desired relation to the carrier rods 1, 2 and 3 which are driven thereby, jam nuts 44 holding bolts 43 in adjusted position. Owing to springs 62 and 67 the motions of cam followers 53 and 54 are transmitted through trains of parts which are yieldable irrespective of the directions of movement of levers 32 and 33, whereby no damage results in case any portion of either of said levers strikes an obstruction, an occurrence which their manner of use renders quite possible.

Levers 32 and 33 have fingers 68 and 69 (Figs. 30 and 8) for engagement with dogs 72 on the carrier rods 1, 2 and 3 and are operated by the cams 57 and 58 to alternately connect and release the carrier rods in a manner similar to that shown in the aforesaid Patent No. 2,219,733.

In this instance, the carrier rods are operated in 2, 3, 1 sequence, that is, the carrier rod 2 is the first carrier rod engaged by the levers 32 and 33, the carrier rod 3 is the second to be engaged and the carrier rod 1 is the third and last carrier rod to be engaged in the sequence. The carrier rod 2 being the first carrier rod to be operated, rod 1 is the last one to be operated in knitting the “ringless” portion of the fabric. However, the operation of the carrier rods as recited, is only an illustration of one sequence of operation, and I do not limit myself to this.

When it is desired to discontinue operation of the attachment 25 at the end of the last yarn laying stroke of the alternating attachment 25, in which the carrier rod 1 is moved from left to right, as viewed in Figs. 2 and 3, the levers 32 and 33 are shifted to engage rod 2 and remain in the position in which they engage or are adapted to engage the carrier rod 2 until after it has again been operated. At this time the detent member 41 is withdrawn from engagement with the flat portion 42 of the shaft 37 and the lever 38 is rotated in a counterclockwise direction from the position shown in Fig. 6, to the position of Fig. 8, in which position the detent member 41 is again engaged with the flat portion 42 of the shaft 37 which action moves the levers 32 and 33 to inactive position relative to the dogs 72 on the carrier rods, as shown in Fig. 8. Also at this time, the pawl and ratchet means on the auxiliary cam shaft is disabled to prevent further rotation of the auxiliary cam shaft and the attachment 25 is released from the friction-box rod 18. The attachment is maintained in this condition until the carrier rods are again to be sequentially operated.

In order to prevent engagement of any carrier rod except carrier rod 2 at the start of the next sequential operation of the carrier rods, there is provided a control means 75 (Figs. 4, 5 and 7)

which prevents movement of the lever 38 unless the auxiliary cam shaft 59 is in proper position to start the "ringless" sequence. The control means 75 comprises a cam 76 mounted on the shaft 59 to rotate in fixed relation with the cams 57 and 58. The cam 76 cooperates with a cam follower 77 carried on an arm 78 of a lever 79 pivotally mounted on a bracket 82 secured to the friction box 26. The cam follower 77 is biased toward the cam 76 by means of a spring 83 which is connected between a pin 84 on the lever 79 and a pin 86 on the bracket 82. The lever 79 has a second arm 87 which is adapted to overlie the path of movement of an end 88 of lever 38 when it is in the position of Figs. 5 and 8.

With this arrangement, when the lever 38 has been moved to the position shown in Fig. 8 and the pawl and ratchet mechanism (not shown) for the shaft 59 has been disabled to prevent rotation of the shaft while the alternating attachment is inactive, the cam follower 77 will be in engagement with a low part 89 of cam 76 (Fig. 7) and the arm 87 positioned out of the plane of movement of the end 88 of the lever 38 as shown in Figs. 4 and 6, whereupon the lever 38 may be turned in a clockwise direction as viewed in Fig. 8, to reengage the levers 32 and 33 with the carrier rod 2 to start the ringless knitting. However, if for some reason the shaft 59 and cam 76 are accidentally rotated to the position in which the levers 32 and 33 are wrongly placed and would if lever 38 were turned back to their position shown in Fig. 6, strike against some other part or parts, then the cam follower 77 is in engagement with the high portion of the cam 76, as shown in Figs. 5 and 8, and the arm 87 of the lever 79 will overlie the plane of movement of the lever 38, as shown in Figs. 5 and 8, so that it cannot be moved from its position of Fig. 8 to reengage the levers 32 and 33 to the carrier rod 2 until the shaft 59 is again turned to engage the low part 89 of the cam 76 with the cam follower 77. The operator, being thus apprised that the parts are in the wrong relative positions, takes the necessary steps to correct the adjustment and positions of the parts before again starting the friction-box 26 for "ringless" knitting.

Of course, the improvements specifically shown and described by which I obtain the indicated results, can be changed and modified in various ways without departing from the invention herein disclosed and hereinafter claimed.

While I have disclosed herein a means for preventing the start of operation of the carrier rod selecting means except when in a predetermined position, I do not claim this combination broadly, this combination in its broad aspect being shown and claimed in the prior application of Gottlob Bitzer, filed March 27, 1942, Serial No. 436,414, for Yarn carrier rod operating means for knitting machines.

I claim as my invention:

1. In a knitting machine having yarn carrier rods, means for driving said carrier rods comprising a friction box, means associated with said friction box including a pair of elements for connecting said yarn carrier rods to and releasing them from said friction box in predetermined sequence, means on said friction box for moving said carrier rod connecting and releasing elements from active to inactive position when said connecting and releasing elements are in predetermined relation to said yarn carrier rods and means carried by said friction box for preventing return of said elements from said inactive to ac-

tive position relative to said yarn carrier rods unless said connecting and releasing means is in said predetermined relation to said yarn carrier rods.

5. 2. In a knitting machine having yarn carrier rods, means for driving said yarn carrier rods comprising a friction box, elements for connecting said yarn carrier rods to and releasing them from said friction box in predetermined sequence, an auxiliary cam shaft, cam means on said friction box operated by said auxiliary cam shaft for operating said element connecting and releasing means, means on said friction box for moving said elements from active to inactive position when said connecting and releasing means are in predetermined relation to said carrier rods, means including a lever on said friction box adapted to engage said element moving means thereby preventing movement of said elements from said inactive to active position relative to said carrier rods unless said elements are in said predetermined relation to said yarn carrier rods.

3. In a knitting machine having yarn carrier rods, means for driving said carrier rods comprising, a friction box, a pair of elements for connecting said yarn carrier rods to and releasing them from said friction box in predetermined sequence, an auxiliary cam shaft, cam means on said friction box operated by said auxiliary cam shaft for operating said elements to connect and release said carrier rods, means on said friction box for moving said elements from active to inactive position when said connecting and releasing means is in predetermined relation to said carrier rods, means including a cam member carried on said friction box in predetermined relation with respect to said element operating cam means and a lever on said friction box cooperating with said cam member for preventing movement of said elements from inactive to active position relative to said carrier rods unless said connecting and releasing means is in said predetermined relation to said yarn carrier rods.

4. In a knitting machine having yarn carrier rods, means for driving said yarn carrier rods comprising, a friction box, a pair of elements carried by said friction box for connecting said yarn carrier rods to and releasing them from said friction box in predetermined sequence, an auxiliary cam shaft, cam means for said friction box operated by said auxiliary cam shaft for operating said elements to connect and release said carrier rods, means on said friction box for moving said elements from active to inactive position when said cam means is in predetermined relation to said connecting and releasing elements, means including a cam member carried on said friction box and operated in predetermined relation with respect to said element operating cam means and a lever on said friction box cooperating with said cam member adapted to overlie the path of movement of said element moving means to prevent movement of said elements from inactive to active position unless said cam means is in said predetermined relation to said connecting and releasing means.

5. In a knitting machine having yarn carrier rods, means for driving said yarn carrier rods comprising a friction box, a pair of elements carried by said friction box for connecting said yarn carrier rods to and releasing them from said friction box in predetermined sequence, an auxiliary cam shaft, cam means on said friction box operated by said auxiliary cam shaft for

operating said elements to connect and release said carrier rods, means on said friction box for moving said elements from active to inactive position when said elements are in a predetermined position in said carrier rod connecting and releasing sequence, means including a cam member carried on said friction box in predetermined relation to said element operating cam means and a lever also carried on said friction box cooperating with said cam member and adapted to prevent return of said elements from inactive to active position unless said elements are at said predetermined position in said carrier rod connecting and releasing sequence.

6. In a knitting machine having yarn carrier rods, means for driving said yarn carrier rods comprising a friction box, a pair of elements carried by said friction box for connecting said yarn carrier rods to and releasing them from said friction box in predetermined sequence, an auxiliary cam shaft, cam means on said friction box operated by said auxiliary cam shaft for operating said elements to connect and release said carrier rods, a second cam means on said friction box operated in predetermined relation to said first cam means and having high and low cam portions, a lever carried on said friction box cooperating with said second cam means and means for moving said pair of elements from active to inactive position relative to said yarn carrier rods when said lever is in engagement with the low portion of said second cam means, said lever adapted to overlie the path of movement of said element moving means to thereby prevent return of said elements from inactive to active position except when said lever is in engagement with said low portion of said second cam means.

7. In a multiple carrier friction box attachment for ringless knitting, in combination, elements for driving yarn carrier rods pivoted on an axis on the friction box, an auxiliary cam-shaft mounted to rotate in the friction box having cams for turning said elements, cam followers cooperating with said cams and adapted to transmit thrusts to said elements, means including a lever mounted to swing in a plane

at right angles to said axis whereby said elements may be shifted from effective to ineffective position, and back again, and means for latching said lever in the position in which said elements are held in ineffective position whenever said cams lie between certain angular positions relative to said followers, said last means including a second lever pivoted on the friction-box having a cam follower supported therefrom and having an arm extending, when the second lever is in a certain angular position, into position to latch said first lever in the position in which said elements are ineffective and a cam on said auxiliary cam-shaft adapted to cooperate with said last follower to hold said second lever in latching position so long as the auxiliary cam-shaft is between certain angular positions relative to the last mentioned follower.

8. In a multiple carrier friction-box attachment adapted for ringless knitting, connecting means pivoted on an axis on the friction-box for driving yarn carrier rods, an auxiliary cam-shaft mounted to rotate on the friction-box having cam means for turning said connecting means, follower means for cooperating with said cam means and adapted to transmit thrusts from said cam means to said connecting means, means including a lever mounted to swing in a plane at right angles to said axis whereby said connecting means may be shifted from effective to ineffective position and back again, and means for latching said lever in the position in which said connecting means is held in ineffective position, said latching means including a second lever pivoted on the friction-box to swing in a plane at right angles to the plane of movement of said first lever and having a cam follower supported therefrom and having an arm extending, when the second lever is in a certain angular position, into position to retain said first lever in the position in which said connecting means is ineffective and a cam on said auxiliary cam-shaft adapted to cooperate with said last follower to hold said second lever in retaining position so long as the auxiliary cam-shaft is between certain angular positions relative to the last mentioned follower.

HERBERT ERICH HAEHNEL.
